DESIGN FOR A SEMITRAILER TANK BODY

Donald A. Bering and Delos W. Davisson, San Francisco, Calif., assignors to Shell Oil Company, San Francisco, Calif., a corporation of California

Application March 21, 1934, Serial No. 51,136

Term of patent 3½ years

To all whom it may concern:

Be it known that we, Donald A. Bering and Delos W. Davisson, both citizens of the United States and residents of San Francisco, California, have invented a new, original, and ornamental Design for a Semi-Trailer Tank Body, of which the following is a specification, reference being had to the accompanying drawing, forming a part thereof.

Figure 1 is a side elevation of the semi-trailer tank body.

Figure 2 is a rear end elevation thereof.

As a feature of this design attention is drawn to the elongated dome surmounting the tank and the shelves extending along the sides of the tank positioned near its mid point.

We claim:

The ornamental design for a semi-trailer tank body, as shown and described.

In testimony whereof, we have hereunto set our hands this 12th day of March, 1934.

DONALD A. BERING.
DELOS W. DAVISSON.
